PAUL SASSO AND JOHN P. FARUGIA, OF ALEXANDRIA, EGYPT.

WATER-HEATER.

No. 904,366.

Specification of Letters Patent. Patented Nov. 17, 1908.

Application filed August 8, 1907. Serial No. 387,641.

To all whom it may concern:

Be it known that we, PAUL SASSO, a citizen of the United States, and JOHN P. FARUGIA, a subject of the King of Great Britain, both residents of Alexandria, Egypt, have invented a new and Improved Water-Heater, of which the following is a full, clear, and exact description.

This invention relates to water heaters, and the object of the invention is to produce a heater having a large heating surface, to the end that the water will become quickly heated.

While the specification describes the device as employing liquid fuel, it may be used with fuels of any kind.

The invention consists in the construction and combination of parts to be more fully described hereinafter and particularly set forth in the claims.

Reference is to be had to the accompanying drawings forming a part of this specification, in which similar characters of reference indicate corresponding parts in all the figures.

Figure 1 is a vertical central section through a heater constructed according to our invention, the lower portion of the figure being shown in elevation; Fig. 2 is a plan of a bell which constitutes a feature of the invention; and Fig. 3 is a plan of a baffle disk or draft disk which controls the flow of the gases of combustion as they pass upwardly from the burner.

Referring more particularly to the parts, 1 represents the body of the device, which is preferably of cylindrical form as shown, and formed of an outer shell 2 and an inner shell 3, forming a water jacket therebetween as illustrated. The lower portion of the body is expanded to form a base 4 mounted upon suitable legs 5 as indicated. In the upper portion of the body a transverse double walled head 6 is provided. In the upper portion of the body 1 and centrally disposed therein, there is mounted a flue 7 which is of conical form as shown, the upper end of the cone being cut off. This cone is formed with a double wall presenting an outer shell 8 and an inner shell 9 forming a water jacket therebetween. The lower portion of this cone or flue is in communication with the water head 6 through the medium of a circulation pipe 10. In the lower portion of the body a burner 11 is provided, which is supplied with liquid fuel from a suitable

reservoir 12 attached at the side of the base as indicated.

In the lower end of the flue or cone 7 a bell 13 is suspended; the lower edge of this bell lies around the outer edge of the burner 11, and the bell operates as a guide to direct the gases of combustion upwardly through the flue or cone. The burner 11 is simply of cylindrical form, having a plurality of openings 14 through which the fuel escapes and at which the ignition takes place.

The upper end of the body 1 is formed into a bonnet 15 having an upwardly projecting central neck 16, said neck being provided with a transverse bar 17. From the central point of this bar a suspending wire 18 is provided, which hangs vertically downward into the interior of the cone or flue 7. Near the lower portion of the flue this wire 18 supports a baffle disk or flue plate 19, the form of this plate being clearly shown in Fig. 3. It is of circular form, provided with a serrated edge 20 and having a plurality of openings 21 distributed through its body. 80 The wire 18 extends below the plate and affords means for supporting the bell 13. To facilitate this arrangement, the bell is provided with a transverse bar 22 similar to the bar 17 referred to above. The water passes 85 into the water jacket of the body 1 through an inlet pipe 23, and the water is drawn off from the device through an outlet pipe 24 which passes out of the body on the opposite side. This pipe 24 is disposed in a loop or 90 coil 25, of substantially triangular form, located within the upper portion of the cone and above the baffle plate 19. It will be observed that the upper portion of the cone is not directly in communication with the interior of the water head 6. The coil or loop 25 is attached to the upper extremity of the cone, so that the water which passes from the device is drawn off at this point. In this way, on account of the lack of direct communication between the cone and the head at this point, the water is made to circulate 95 down through the pipe 10 into the lower portion of the cone, whence it moves upwardly before being drawn off through the coil 25. 100 In this way it will be observed that the water is heated methodically for it will be understood that the coil 25 is located at the hottest point in the entire course of the water. The baffle plate 19 restricts the upward flow of the hot gases of combustion 110 and operates to force the principal portion

of the gases to pass the plate at the serrated edge. In this way the gases are made to come closely in contact with the inner wall of the cone.

5 The construction of the device is such as to stimulate the circulation of the water toward the delivery pipe 24. This will be evident from a consideration of the operation of the conical flue 7. The water is admitted 10 at the lower end of this flue, and as it boils, the upward movement of the steam tends to produce an upward current of the water in the cone. In this way an upward circulation is induced, which tends to draw in the water 15 from the water head, and operates to deliver the water from the upper end of the cone to the pipe 24. It is evident, also, that the water in the flue will have a higher temperature than the water in the jacket of the body, 20 or in the water head, and hence, the water which passes through the device is heated in a most advantageous manner. This tendency of the device to produce a circulation is especially valuable where the heater is 25 used in a heating system of pipes, and where the water which is delivered to the pipe 24 eventually returns through the pipe 23.

Special attention is called to the fact that in this water heater the water is heated 30 methodically, that is, it is presented first to heating surfaces which are not heated to the highest extent, it then passes to more highly heated surfaces, and is finally subjected to the highest temperature in the coil 25, which 35 is disposed in the flue, where the heat is concentrated. At this point the area of the heating surface is very high as compared with the volume of the tube or coil.

It will be evident that the water jacket 40 around the body which first receives the incoming water, receives less heat than the water head 6. It is also evident that the water jacketed flue 7 receives more heat than the water head, and at the coil or loop 25 45 through which the water passes from the flue, the water receives the most heat. Attention is also called to the fact that the connection of the coil or loop 25 to the flue, is made at the upper end of the flue so that the 50 ebullition of the water in the flue jacket will tend to produce an upward movement of the water in the flue, and in this way the outward circulation of the water through the loop is assisted.

55 If the device is to be used with a solid fuel, instead of employing a burner such as that shown, a grate or fire pot will be arranged in the device at substantially the same location as the burner illustrated.

60 Having thus described our invention, we claim as new and desire to secure by Letters Patent:

1. A heating device consisting of a cylindrical body with a water jacket and having

a transverse water head with an opening 65 therethrough, a conical water jacketed flue below said head, a burner below said flue, a bell over said burner and under said flue for directing the gases up said flue, a baffle plate disposed in said flue and directing the body 70 of gases along the wall of said flue, a member supporting said bell and said baffle and passing downwardly through said opening and said flue, a pipe connecting said flue with the water jacket of said body, and a 75 pipe leading from said flue to carry the water from said device.

2. A heating device consisting of a cylindrical shell having a water jacket and a transverse water head with an opening 80 therethrough, a flue within said body below said head, a water jacket for said flue, a pipe passing down through said opening and connecting said water head with said second-named water jacket, and a pipe coil disposed 85 within said flue, passing upwardly through said opening and leading the water from said flue.

3. A heating device consisting of a body having a water jacket and a transverse water 90 head, said water head having a central opening therein, a conical flue below said head converging toward said opening to direct the heated gases therethrough, a water jacket on said flue, a pipe passing downwardly through 95 said opening and connecting said water head with said flue, and a pipe passing upwardly through said opening and carrying off the water from said second-named water jacket.

4. A device of the class described, comprising a body having a water jacket, a conical flue within said body also having a water jacket in communication with said first water jacket, a baffle plate in the lower portion of said flue, and adapted to deflect the 105 gases along the wall of said flue, and a coil leading the water from said device and disposed in said flue above said baffle plate.

5. A heating device consisting of a body having a water jacket, a conical flue also 110 having a water jacket communicating with said first water jacket and disposed in the upper portion of said body, a baffle plate suspended in the lower portion of said flue and having a form adapted to direct the gases 115 along the inner wall of said flue, a burner below said cone, and a bell supported over said burner and directing the gases of combustion upwardly therethrough.

In testimony whereof we have signed our 120 names to this specification in the presence of two subscribing witnesses.
